NOZZLE HANDLE ASSEMBLY FOR A MEDICAL IRRIGATOR OR THE LIKE

Maxie E. Slee, Loveland, Colo., and Allan B. Johnson,
Tarzana, Gerald Wm. Lee, Glendale, and Michael
A. Cammack, North Hollywood, Calif., assignors to
Aqua Tec Corporation, Fort Collins, Colo., a corpo-
ration of California

Filed Sept. 3, 1968, Ser. No. 13,355

Term of patent 14 years

Int. Cl. D24—03
U.S. Cl. D83—12

FIG. 1

FIG. 2

FIG. 3

FIG. 4

FIG. 5

FIG. 6

FIG. 1 is a perspective view of a nozzle handle assembly for a medical irrigator showing our new design;

FIG. 2 is a side elevation view of the nozzle handle assembly of FIG. 1;

FIG. 3 is a front elevation view thereof;

FIG. 4 is a rear elevation view thereof;

FIG. 5 is a top plan view thereof; and

FIG. 6 is a bottom plan view thereof.

The side opposite that shown in FIG. 2 is a mirror image of FIG. 2.

The portions shown in broken lines are for illustrative purposes only and form no part of the claimed design.

We claim:

The ornamental design for a nozzle handle assembly for a medical irrigator or the like, as shown and described.
